US00D859393S

(12) **United States Design Patent** (10) **Patent No.:** **US D859,393 S**
(45) **Date of Patent:** **** Sep. 10, 2019**

(54) **ELECTRONIC DEVICE MOUNT**

(71) Applicant: **mophie inc.**, Tustin, CA (US)

(72) Inventors: **Dat Minh Dang**, Westminster, CA (US); **Nguyen To**, Corona, CA (US)

(73) Assignee: **mophie inc.**, Irvin, CA (US)

(**) Term: **15 Years**

(21) Appl. No.: **29/632,207**

(22) Filed: **Jan. 5, 2018**

(51) **LOC (12) Cl.** **14-03**

(52) **U.S. Cl.**

USPC **D14/253**; D12/415

(58) **Field of Classification Search**

USPC D14/251-254, 217, 224, 224.1, 238.1, D14/299, 434, 447, 451-452, 483; D12/400, 415-426, 426.1, 114, 223; D8/394; D6/513, 553, 567; D3/218; D16/242, 245; D10/74

(57) **CLAIM**

The ornamental design for an electronic device mount, as shown and described.

DESCRIPTION

FIG. 1 is a top-front perspective view of the design for the electronic device mount;

FIG. 2 is a bottom-rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken line portions in the drawings are shown to illustrate environment only and form no part of the claimed design.

1 Claim, 8 Drawing Sheets
